(57) **CLAIM**

The ornamental design for a rust removal robot as shown and described.

DESCRIPTION

1. Rust removal robot

1.1 : Perspective

1.2 : Front

1.3 : Back

1.4 : Top

1.5 : Bottom

1.6 : Left

1.7 : Right

Description of images: fig.1.1 is a perspective view of a rust removal robot showing the new design; fig. 1.2 is a front view thereof; fig. 1.3 is a back view thereof; fig. 1.4 is a top view thereof; fig. 1.5 is a bottom view thereof; fig. 1.6 is a left view thereof; and fig. 1.7 is a right view thereof: product description: the rust removal robot can be used to perform cleaning and de-rusting on steel or iron structures.

The broken lines depict portions of the rust removal robot that form no part of the claimed design.
